UNITED STATES PATENT OFFICE.

JOHN J. CLAUSE, JOHN R. WOODLOCK, AND JOSEPH BICHL, OF CHICAGO,
ILLINOIS.

MECHANISM FOR COUNTING FOLDED NEWSPAPERS.

SPECIFICATION forming part of Letters Patent No. 243,690, dated July 5, 1881.

Application filed October 10, 1879.

To all whom it may concern:

Be it known that we, JOHN J. CLAUSE, JOHN R. WOODLOCK, and JOSEPH BICHL, all residing at Chicago, in the county of Cook and State 5 of Illinois, and citizens of the United States, have invented new and useful Improvements in Mechanism for Counting Folded Newspapers, of which the following is a full description, reference being had to the accompanying drawings, in which—

Figure 1 is a top or plan view; Fig. 2, a side elevation; Fig. 3, an end view; Fig. 4, a detail showing devices for operating the movable guide or stop.

The object of this invention is to deliver the papers from a folding mechanism attached to a web-printing press, so as to produce a perfect separation of or division between the papers when folded and enable an accurate count 15 to be made, which separation or division shall be automatically performed, and shall divide the folded papers into series having a uniform number; and its nature consists in providing a movable guide or stop and a stationary guide 20 or stop so arranged that the papers of a series will be folded at different points in relation to each other by the folding devices, and will be delivered as folded; in providing a circular disk having an intermittent rotary movement 25 for operating the movable guide or stop; in providing the disk with one or more pins so located in reference to the teeth of the ratchet-wheel and an arm or mechanism for raising the movable guide as that a pin will engage 30 and operate the movable guide at uniform intervals.

In the drawings, A represents the movable guide; B, the stationary guide; C, the arms supporting the movable guide or stop; D, the 35 rock-shaft carrying the movable guide or stop; D', the supports for the rock-shaft; E, the revolving disk; E', the spindle or axis on which the disk is mounted; F, the hub or central portion of the disk E; G, the ratchet-wheel; H, the vibrating arm or lever for moving the ratchet-wheel; I, the pitman; J, the eccentric; K, the shaft carrying the eccentric; L L', the 45 shafts carrying the tape-pulleys; M M, the folding-rollers; N, the cross-bar supporting the 50 folding-blade, (not shown;) O O' O'', the sup-

porting-frame; P P' P'', the cross-bars of the frame; Q, the cross-bar which, with the cross-bar P, supports the shafts of the folding-rollers; a, the pins or projections on the revolving disk; b, the arm for operating the rock-shaft; c, the 55 arm or lever for returning the rock-shaft; d, the coil-spring; e, the ratchet-teeth; f, the sliding catch or pawl; g g', the pulleys carrying the tapes; h, the tapes.

The stops or guides A B are located near the 60 outer end of the folding-rollers and at a short distance apart, and are arranged so as to be parallel with each other and transverse to the movement of the papers over the folding-rollers. The inner stop, A, is movable, so that it 65 can be raised up and allow one or more papers to pass beneath it and come in contact with the stop B, which is stationary, and both stops A B act as guides for folding the papers on different lines. The stop or guide A is made 70 in sections, with an opening or passage between for the passage of the folding-blade, and the stop or guide B is made in one piece, as shown, extending across the end of the folding-blade at a sufficient distance therefrom not to interfere with the vertical movements of the 75 blade, and have it act to fold the papers.

The stop or guide A, as shown, is attached to the outer ends of arms or supports C, rigidly secured at their inner ends to a rock-shaft, D, 80 which has its bearings in the supports D' in the sides of the frame. One end of this shaft D projects beyond the side of the frame, and to its end is firmly secured a short arm, b, by means of which the shaft can be rocked in its 85 bearings, so as to raise the stop or guide A sufficiently to allow the papers to pass between it and the folding-rollers and come in contact with the stationary stop or guide B, such upward movement of the guide A occurring at 90 regular intervals, in order to divide the papers into series of a uniform number.

The disk E is mounted on a spindle, E', suitably supported on the frame, and is to be given an intermittent rotary movement. This 95 disk, near its periphery, has a series of holes, located at equal distances apart to receive pins or studs a, which project out from the face of the disk, and are so arranged as to be brought successively in contact with the arm b as the 100

disk E is revolved. The pins or studs *a* are secured in place in such manner as to be removable, so that a portion or all but one can be taken out for the purpose of varying the intervals at which the stop or guide A is operated, so as to increase or diminish the number of papers in each series.

The wheel G is mounted and revolves on the spindle or axis E', and has on its periphery a series of ratchet-teeth, *e*, and is firmly secured to the hub or small circular projection F of the disk E, so that when the wheel G is actuated motion will be imparted to the disk E. As shown, the wheel G is of sufficient diameter to have on its periphery fifty teeth; but its diameter may be increased or diminished so as to provide a greater or less number of teeth, the number, for convenience, being one that can be subdivided into series of fives or tens whenever so desired. This subdivision in the form of mechanism shown is effected by locating the holes in the disk E which receive the pins or studs *a* so that a pin or stud can be placed to make the desired division. As shown, five pins or studs *a* are used, which makes five series of teeth of ten each when the entire number of pins are employed, or fifty when only one, or twenty-five with two of the pins. The number of pins can be increased to ten, making a subdivision of five, and the number of teeth *e* can be increased to a hundred or more, with pins or studs *a* arranged to make the desired subdivisions. The wheel G is carried forward one tooth as each paper is folded, and the disk E is advanced accordingly a distance equal to the space between each tooth or notch *e* as a paper is folded, which advancement brings the pins or studs *a* into contact in succession and in regular order with the arm *b*, so that at the completion of each series the stop or guide A will be raised, and one paper will be folded in the line of the guide or stop B in the form of device shown, thereby projecting one paper, so as to make a distinct separation between the series.

In the construction shown a lever or arm, H, carrying a sliding catch or point, *f*, to engage with the teeth or notches *e*, is provided for actuating the wheel G. This lever or arm H has a vibrating movement given to it by a pitman, I, operated by an eccentric, J, on the end of a shaft, K, mounted in suitable bearings on the frame, which shaft may be driven from the shaft of the folding-blade, (not shown,) or in any other suitable manner, so that the eccentric will operate to carry the arm or lever H forward at each descent of the blade and return it as the blade ascends, each forward movement of the lever advancing the wheel G and disk E.

Other forms of devices can be used for giving the wheel and disk a forward movement

in unison with the descent of the folding-blade and advancing the disk one notch as each paper is carried between the folding-rollers.

The shafts L L' are located at each end of the frame, and are mounted in suitable bearings on the frame, and carry pulleys *g* *g'*, over which the ordinary tapes, *h*, for delivering the papers over the folding-rollers run.

The folding-rollers M are supported in suitable bearings on the cross-pieces P Q of the frame, and are arranged and operate in the usual manner. An ordinary folding-blade supported in suitable guides by the cross-bar N is to be used, the bar N supporting the blade so as to carry the papers between the folding-rollers M and fold each paper or sheet at or near the center.

The frame-work O O' O'' may be of any form of construction suitable for the purpose of furnishing a support for the folding mechanism and the automatic counting devices.

In use the sheets are carried by the tapes *h* over the folding-rollers M, and the folding-blade descends and forces the sheets between the rollers, which complete the folding in the usual manner, each descent of the folding-blade carrying the disk forward, as before described.

In the arrangement shown only one paper is advanced or projected beyond the others of the series to produce a separation between the series.

To make a separation between series of ten the papers will be folded at the stop A, the wheel E advancing one notch as each paper is folded without affecting the stop until the tenth notch is reached, at which time the pin or stud *a* will strike the arm *b* and raise the guide A, and the next paper will pass beneath the guide A against the stop or guide B and be folded at that point, so that such paper will project beyond the other papers a distance equal to the distance between the two guides A B, producing a variable delivery of the folded papers. The next series is counted in the same manner, the papers being stopped for folding against the stop or guide A, which is returned by the action of the spring *d*, which, through the arm *c*, returns the rock-shaft D and stop A in position for the stop to act until again raised by a pin or stud, *a*, striking the arm *b*, and these movements will continue as long as the papers are delivered to the folding-rollers.

The separations into other series than tens is effected in the same manner, the pins or studs being located so as to produce the required series, a paper being projected by being folded when in contact with the guide or stop B, while the others are folded when in contact with the stop or guide A.

It is evident that the disk E might have a series of flanges so arranged as to raise the stop A for an entire series, so that one series would be folded at the stop or guide B and another at the stop or guide A, and that other forms of mechanism can be used in carrying out the invention, which is the separating of

folded papers into series having a uniform number by giving them a variable delivery, so that one or more papers will be projected beyond the ends of the papers of the series.

5 By this arrangement it will be seen that papers can be separated into series having a uniform number in each series, which separation will enable an accurate count to be made by reason of the variable delivery, producing a well-defined line of separation of one series from another, and that the series can be made to contain a larger or smaller number of papers, and the papers in each series must be the same in number in each instance, and the papers

10 are delivered folded and counted automatically in series of a uniform number.

What we claim as new, and desire to secure by Letters Patent, is—

15 1. In a newspaper folding and counting machine, the combination of the stationary guide or stop B, the adjacent movable guide or stop

A, arranged to be raised and lowered at predetermined intervals, the paper-carrying tapes h, and the folding-rollers M, located beneath the tapes and the guides or stops, substantially 25 as and for the purposes herein described.

2. The combination, with the stationary guide or stop B and the movable guide A, attached to a rock-shaft, D, provided with the arm b, of the intermittently-rotating disk E, 30 provided with one or more removable pins, arranged to operate the arm of the rock-shaft and lift the movable guide or stop at predetermined intervals, substantially as and for purpose herein described.
